(57) **CLAIM**

The ornamental design for a light fixture, as shown and described.

DESCRIPTION

FIG. 1 is a side elevational view of the invention;
FIG. 2 is a front elevational view of the invention at a right angle to the view of FIG. 1;
FIG. 3 is a back elevational view of the invention;
FIG. 4 is a bottom view of the invention;
FIG. 5 is a perspective view of the invention;
FIG. 6 is another perspective view of the invention from a direction opposite that of FIG. 1;
FIG. 7 is a side elevational view of a second embodiment of the invention;
FIG. 8 is a front elevational view of the invention at a right angle to the view of FIG. 7;
FIG. 9 is a back elevational view of the invention;
FIG. 10 is a bottom view of the invention;
FIG. 11 is a perspective view of the invention; and,
FIG. 12 is another perspective view of the invention from a direction opposite that of FIG. 11.
